RACK

Freedom Parker, Akron, Ohio

Application September 24, 1932, Serial No. 634,776

1 Claim. (Cl. 311—103)

My invention relates to racks more particularly to racks for supporting articles such as beverage glasses, bottles, etc. on card tables, to keep said articles within easy reach of the players, 5 and it consists in the combinations, constructions and arrangements herein shown and described.

The primary purpose of my invention is to provide a device of the type described that will hold glasses, bottles, cigarettes or other small articles 10 used by players during card games for ready use by the players, yet in an out-of-the-way position insofar as the top or playing surface of the table is concerned.

Another object of the invention is to provide a 15 device of the kind described that is readily adaptable for use on tables having top surfaces of variable thickness.

Other objects and advantages will appear as the specification proceeds and the invention will 20 be more particularly defined in the appended claim.

My device is illustrated in the accompanying drawing forming a part of this application, in which

25 Figure 1 is a perspective view of my invention positioned for use, and

Figure 2 is a rear elevational view of the device.

Figure 3 is a transverse sectional view of the device.

30 In carrying out my invention I make use of the corner portion 1 of a conventional form of card table used in the playing of bridge, five hundred, etc. It is to this corner portion that I secure my rack.

35 This rack consists of a clamp portion 2 and an article supporting part or parts 3 and 4. The clamp portion 2 comprises a box-like formation having vertically extending walls 5 intersecting at right angles as shown at 6 and horizontally 40 extending walls 7 of triangular form at the top and bottom of walls 5. The upper wall 7 is designed to act as one jaw of the clamp member which fastens the device to the table. The other jaw consists of the horizontally extending member 45 8, supported by the screw element 9. This operating element 9 is threadedly engaged in boss 10, which is integral with the lower wall 7. The

jaw member 8 has its end parts or edges 11 cut at an angle to engage walls 5 and be guided thereby, in a manner easily understood.

For supporting the glasses, bottles or other articles, as desired, I provide platforms 12, which extend from walls 5. These platforms may be hollowed out as indicated at 13 to assure retention of articles thereon.

For further assuring retention of the articles on the platforms, I provide a strap member 14, which may take any convenient form, but which is shown in this embodiment as having a contour formed along the outlines of the platform members. This strap is supported by fasteners 15, secured to walls 5.

From the foregoing description the use of my device is easily understood. The box-like part is simply placed over the corner of the table as shown in Figure 1 with the underside of top-wall 7 in abutting relationship with the top surface of the table. Screw 9 is then operated to bring element 8 into engagement with the underside of the top of the table. With the device thus set up glasses, bottles or similar articles can be placed on the platforms 12 and be ready to the hands 25 of the players and yet removed from the playing surface of the table.

It is thus seen that I have provided a rack that will support glasses and similar articles from the top surface of a card table within easy reach of 30 the players using said table and yet in an out-of-the-way position insofar as the playing surface of the table is concerned.

I claim:

In a device of the type described, supporting 35 means, and means for securing said supporting means to the corner of a table, comprising a frame having walls for engagement with the top surface of the table and the sides of the table top adjacent the corner thereof, and a member 40 movable relative to said frame and engaged therewith to forcibly abut and engage the bottom surface of the table top, said member having edges engageable with the walls of said frame, which engage the sides of the table top to guide said 45 movable member in straight line reciprocation.

FREEDOM PARKER.
